REFRIGERATOR APPLIANCE

Clarence P. Swanson, Shreveport, La.

Application December 29, 1947, Serial No. 794,219

6 Claims. (Cl. 62—1)

1

My invention relates to refrigerator appliances in general, but more in particular to a removable cold storage unit adapted to be used in connection with a prior art electric refrigerator.

It is one of the objects of this invention to provide a cold storage unit which may be removably inserted into a prior art electric refrigerator and which utilizes the cooling system of the refrigerator as its cooling medium.

It is another object of this invention to provide a supplemental cold storage unit which may be placed adjacent to the cooling coils of a prior art refrigerator on either one side or the other thereof and which provides a compartment substantially insulated from areas other than the cooling area surrounding the cooling coils against which it is placed.

Another object of this invention is to provide a supplemental cold storage unit for a prior art refrigerator which may easily be installed or removed for cleaning, and which has a conveniently placed door for easy accessibility to the interior thereof.

It is another object of this invention to provide a supplemental cold storage unit for prior art refrigerators which is easy to manufacture in various sizes or shapes to suit the refrigerator in which it is to be used.

Other objects and advantages will be found in the course of the following detailed description when viewed together with the accompanying drawing in which:

Fig. 1 is a broken elevational view of a standard form of refrigerator with my invention in a cold storage appliance applied thereto.

Fig. 2 is a perspective view of the appliance unit showing the mounting means removed therefrom.

Fig. 3 is a broken cross-sectional view taken along lines 3—3 of Fig. 2.

Fig. 4 is a broken sectional view taken along lines 4—4 of Fig. 2.

Fig. 5 is another sectional view taken along lines 5—5 of Fig. 2.

Referring to the drawing for a detailed description of the invention, the reference numeral 10 represents a domestic refrigerator cabinet having a cooling unit 11 provided with a door 12 whereby access is had to the main cooling compartment 13. In this main cooling compartment 13 the ice cubes are frozen and there is usually a small space either above or below the trays for the storage of frozen foods. While this space can advantageously be used, there is never room enough to store foods in any quantity. Meats kept in such a place of storage must be sufficiently wrapped

to prevent odors from the cooling unit from penetrating them and rendering them ill tasting. Due to the usual small capacity of such a storage locker, the average housewife is careful in choosing not only the quantities but also the kinds of meats or other frozen foods that must be kept for a period of several days.

My invention as a supplemental food storage locker is best understood by reference to Fig. 2 of the drawing which shows an elongated box-like structure having three sides and one of its ends closed. While the device may be constructed of various materials, I have preferred to form the various wall sections of two separate sheets of metallic material, thus making an outer wall 14 and an inner wall 15. Between these two walls is a layer of heat insulating material 20, which may be cork or a finely granulated lava rock bearing the trade name of Pearlite, which has an extremely low coefficient of heat conduction.

The opening 16 in one of the side walls is surrounded by a rubber gasket 17 which is provided with a groove 18 adapted to be forced over a projecting rim 19 formed on the circumferential edge of the opening 16.

The forward end of the unit is provided with a hinged door 21, a cross section of which is shown in Fig. 5. It will be noted that the door is also formed of an inner wall section 22 and an outer wall section 23, and the space between filled with the insulating material 20. The circumferential edges of the door 21 are made to form an offset 24 into which is placed a rubber ring or washer 25 adapted to seal the door against the edges of the opening in the unit when closed. Any form of conventional spring latch may be used to keep the door 21 in the closed position.

In the two opposing walls adjacent to the opening 16 of the unit are small locking slots 26, each slot being adapted to receive the head of a rivet or screw 27 which is attached to a vacuum cup 28. These screws extend through a small spacer bar 29 which keeps the screw heads spaced at the exact distance between the locking slots 26. Such an arrangement also allows the entire unit to be removed or attached with ease and without the necessity of any tools. The locking slots 26 are also placed in the same position on the outside surface of the opposite wall whereby the entire unit may be inverted and mounted on the opposite side of the cooling unit 11.

A brief description of the operation of my device will follow. Let us assume that a housewife is buying foodstuffs in preparation for a special occasion such as a week end, a party or

a holiday, and is anticipating a larger number of servings than usual. Since the occasion is only a temporary one there is no need of purchasing a deep freeze unit or another refrigerator in which to store the extra foodstuffs that must be kept at a low temperature.

Provided with this invention, the housewife will place the heads of the screws 27 of the mounting cups 28 into the locking slots 26 of the unit and slip it into her domestic box 10. After placing the open side 16 up close against the cooling unit 11 to where the rubber gasket 17 yieldably engages it, she will push upwardly on the bottom of the unit until the vacuum cups 28 affix themselves against the upper inside wall surface of the cabinet 10 where they will sufficiently support the unit and its contents until they are removed.

The housewife now is provided with a temporary storage space having a temperature only a few degrees above the inner cooling compartment 13, and in which frozen foods may be safely kept without fear of spoiling. Extra ice cubes may be frozen in the regular manner and placed in storage for special occasions or may even be frozen in the device, if desired. Desserts and salads may be kept without being disturbed as might be occasioned in the former crowded combination freezing and storage locker.

In an actual temperature test made, with the freezing controls of a domestic refrigerator at a normal setting, a small glass of water was placed in the device. After a few hours an inspection showed that the water had completely frozen. It will be remembered that the rubber gasket 17 is pressed snugly against the coils of the refrigerator so that the inner chamber of my device is simply a dead air space, insulated from the general storage area of the refrigerator by insulated wall sections as described above. It will also be noted that my device would perform substantially as well without any insulation at all in the various wall sections. Any kind of partition walls which would provide a dead air space around a portion of the cooling coils of the refrigerator would provide an area which could be maintained at a much lower temperature than the general storage area of the refrigerator.

The device is preferably installed just after the refrigerator coils have been defrosted. In this manner the rubber gasket is permitted to fit snugly against the cooling unit without any interference by ice formations.

Any cracks or openings that might be left between the gasket 17 and the coils of the cooling unit 11 will automatically seal themselves after a few hours by the formation of ice, to effect a complete dead air space within the inner chamber.

When not in use, or for the purpose of cleaning, the unit is easily removed from its position in the refrigerator, either by lifting it from its engagement with the vacuum cups 28 or by removing the cups together with the entire unit. In some instances, where the unit has been in use for several days, the ice will have formed over the rubber gasket to such an extent that it will not free itself easily from the cooling unit 11. In such a case, the unit is lifted to one side, in a manner to release the gasket 17 from its slideable mounting on the rim 19, and the unit removed from its position in the box. The operator will then remove the gasket 17 from the ice formation on the cooling unit 11 and re-attach the gasket to the rim 19.

5 The unit is preferably made of a metallic material having a high heat conducting factor such as aluminum, but may also be molded of a plastic, made of wood or other material to permit flexibility of design or to facilitate manufacturing.

Other changes in the construction and arrangements of parts may be made without departing from the spirit and scope of the invention as defined by the following claims.

10 I claim:

15 1. A food storage box comprised of an outer solid side wall, a solid top wall, a solid bottom wall, a solid rear wall, a front wall having an opening, a door for said opening and a side wall provided with an opening adapted to be positioned adjacent to the cooling coil unit of a domestic mechanical refrigerator, an outwardly disposed bead extending entirely around the perimeter of said opening in said side wall, a flexible washer mounted on said bead and a means for mounting said box on an inner wall surface of a domestic mechanical refrigerator provided with a cooling unit to bring said washer into contact with the cooling coil unit.

20 2. A supplemental food storage container for use in a domestic mechanical refrigerator having a depending cooling coil arrangement exposed in the food storage area of the same, comprising a box provided with an outer side wall, a top and bottom wall and a rear wall, a front opening and a door for said opening, the remaining side wall provided with an elongated opening adapted to be positioned adjacent one of the depending sides of said cooling coil arrangement of said refrigerator, and releasable holding means adapted to hold said box in a suspended position from the inner roof surface of said refrigerator and in a manner to abut said side wall opening of said box to the outer surface of said cooling coil arrangement, whereby the food storage area in said box may be cooled by the cooling coil arrangement of said refrigerator.

25 3. The device as claimed in claim 2 wherein a flexible washer is mounted on said box surrounding the opening in the side wall of the same.

30 4. An auxiliary food storing box for use in a domestic mechanical refrigerator provided with a cooling coil unit, said food storing box provided with side walls, top and bottom walls and front and rear walls, said front wall including a door, said side walls being constructed to resist the transmission of heat therethrough, one of said side walls provided with an opening having a projecting bead around the same, a resilient washer mounted on said bead and a means for mounting said box in a refrigerator comprising locking slots formed in the upper wall of said box, bolts removably inserted into said slots and vacuum cups attached to said bolts.

35 5. The device as claimed in claim 4 wherein both upper and lower walls of said box are provided with locking slots whereby said opening may be disposed in right or left hand positions with respect to a cooling coil unit it is to contact.

40 6. An auxiliary food storage box for use in a domestic mechanical refrigerator provided with a cooling coil unit, said box comprising an elongated structure having an opening in one of its side walls and a door in one of its end walls, means for mounting said box in said refrigerator comprising a plurality of vacuum cups removably attached to the outer surface of a top wall of said box and adapted for engagement with the inner roof surface defining the storage area of 45 said refrigerator, a resilient washer mounted

around said side wall opening of said box, the circumferential edge of said washer being formed into a projecting lip and slanted inwardly toward said opening, said mounting means permitting said box to be positioned at a distance from said cooling unit to effect a yieldable engagement of the lip of said washer with the tangential surface of the cooling coils of said refrigerator, whereby ice formations, created by the cooling coils of said refrigerator, will seal said

washer against said coils to effect a dead air space within said box.
